UNITED STATES PATENT OFFICE

115,074

DESIGN FOR A PORTABLE PRINTING MACHINE

Herman W. Boetticher, Detroit, Mich., assignor to George James, Detroit, Mich.

Application February 3, 1939, Serial No. 82,765

Term of patent 14 years

To all whom it may concern:

Be it known that I, Herman W. Boetticher, a citizen of the United States, residing at Detroit, county of Wayne, in the State of Michigan, have invented a new, original, and ornamental Design for a Portable Printing Machine, of which the following is a specification, reference being made to the accompanying drawings, forming part thereof.

Fig. 1 is a plan view of a portable printing machine showing my new design.

Fig. 2 is a front view thereof.

Fig. 3 is a rear view thereof.

Fig. 4 is a left end view thereof.

Fig. 5 is a right end view thereof.

I claim:

The ornamental design for a portable printing machine, as shown.

HERMAN W. BOETTICHER.
